UNITED STATES PATENT OFFICE.

MEYER D. MINNICK, OF NEWARK, NEW JERSEY, ASSIGNEE, BY MESNE ASSIGNMENTS,
TO NATHANIEL J. LANNON AND RALPH W. SHIELDS, TRUSTEES.

TRACK MAGNET AND CIRCUITS.

Application filed November 23, 1921, Serial No. 517,390. Renewed June 22, 1925.

An object of my invention is to communicate magnetic impulses from a track to rolling stock thereon in an improved manner and to cooperate with a mechanism carried by the rolling stock; for instance, such mechanism as is disclosed by the co-pending application, automatic train control system, jointly invented by Meyer D. Minnick, Julian E. Hampson, Charles W. Burrows, 10 and Charles Messick, filed November 23rd, 1921, Serial No. 517,391.

Other objects are to combine the required number of improved alternating current track magnets with circuits and relays having the least possible departure from standard approved wayside signal practice.

Man failure, which automatic train control guards against, is most dangerous on trunk lines where traffic is densest and 20 heavy fast trains follow each other at short intervals, all going in the same direction, and a typical installation of track magnets and circuits for improved automatic train control under such conditions is described 25 in the detail description from which additional objects may appear.

When blocks are of uniform length and no special conditions are present, the 30 functions of the track magnets in the preferred construction are as follows:

1. Each block is provided with two track magnets, one at the entrance, and one in the middle. These magnets are dead when the block is unoccupied.

35 2. When a block is entered the magnets are energized and made alive for a predetermined length of time, for instance, ninety seconds if the block ahead is unoccupied.

3. The magnets of an occupied block are 40 dead if the block ahead is occupied.

Additional functions may appear from the following detail description in which a track having a straight portion and also special conditions are shown.

45 Referring to the accompanying drawings: Fig. 1 is a diagrammatic view of a track equipped with magnets and wiring.

Fig. 2 and Fig. 3 are continuations of the 50 track of Fig. 1 on a smaller scale, showing the magnets applied to special conditions.

The letter A indicates the extreme left-hand end portion of a block of railroad track, and letters B, C, D, E, F, G, H, I, J and K indicate subsequent blocks equipped

with track magnets for the automatic control of current traffic from left to right, as indicated by the arrows appearing in block C, Fig. 1, and block F, Fig. 2.

The character A¹ indicates a conventional wayside signal in the caution position at the end of block A; B¹ a signal at danger at the end of block B; C¹ a signal at clear at the end of block C; D¹ a signal at clear at the end of block D, which are operated respectively through conventional relays, not shown, by track circuits supplied by conventional batteries A², B², C² and D², connected respectively to the rails of blocks A, B, C and D, by wires A⁴, (the return wire A³ not being shown), B³ and B⁴, C³ and C⁴, 65 70 and D³ and D⁴.

While batteries and signals are not illustrated except as above, all blocks are assumed to be provided with conventional batteries and signals, or at least some form 75 of conventional track circuit, which may be utilized to control the track magnet relays which are of two types, quick action QB, QC and QD, and slow action SB, SC, SD and SDX, respectively.

In the nomenclature used in this specification and in the accompanying drawing, the letters Q and S indicate a type of relay. The letter Q signifies a quick acting relay and the letter S a slow acting relay. When the letters Q or S are combined with a block letter B, C, or D, the location of a relay of a particular type is indicated by the block letter. The letter X indicates an extra relay 85 90 of a particular type.

Where several similarly numbered members, or magnets indicated by the letter N appear and are combined with a block letter A to K, the block letter indicates the block in which the numbered member or magnet N is positioned; however, the block letter is omitted from the numerals in most cases where the numbers first appear in block B.

The first quick acting relay illustrated, of block B, indicated as QB, consists of a winding 10, surrounding an armature 11, upon which are mounted two contact bars 12 and 13. When the winding 10 is energized the armature 11 is lifted, as indicated in Fig. 1, which lifts contact bar 12 out of contact with contacts 14 and 15 and breaks a circuit between them; armature 11 in the indicated position holds contact bar 13 in contact with

contacts 16 and 17, closing a circuit between them. Block C is provided with a similar quick acting relay QC, shown in the down position in the drawing. Block D is provided with a similar relay QD, shown in the up position in the drawing, but its armature 11^P is lengthened downward to carry an extra contact bar 18, which makes contact with contacts 19 and 20 when armature 10 11^P drops.

The first slow acting relay of block B, indicated as SB, consists of a winding 30 surrounding an armature 31, which carries a contact bar 32, making contact with contact slides 33 and 34. In the indicated up position the winding 30 is energized. When winding 30 becomes de-energized the armature 31 falls by gravity but at a slow rate, because of the conventional plunger 35 carried at the lower end of armature 31 and contained within the conventional stationary dash pot 36. The dash pot 36 may be so adjusted by varying the size of the escape hole 37 at the bottom of dash pot 36 that it will 25 take, for instance, 90 seconds for the armature 31 to fall far enough to break contact between contact slide 33, contact bar 32 and contact slide 34. A slight additional fall causes the lower end of armature 31 to come 30 to rest abutting the lug 38 formed upon the bottom of the dash pot 36. Plunger 35 is provided with a conventional inverted leather cup packing 39, so that no dash pot action occurs when armature 31 is lifted by 35 the energization of winding 30. Block C is provided with a similar slow acting relay SC, and block D is provided with two similar relays SD and SDX.

Windings 10 and 30 of relays QB and SB 40 are connected in parallel by wires 40 and 41 and from these wires respectively to the rails of block B by wires 42 and 43. The windings 10^C and 30^C of relays QC and SC are connected in parallel by wires 40^C 45 and 41^C and from these wires respectively to the rails of block C by the wires 42^C and 43^C. The windings 10^P, 30^P and 30^{DX} of relays QD, SD and SDX are connected in parallel by the wires 44 and 45, 50 and 46 and 47, and from wires 44 and 45, to one rail of block D by wire 42^P, and from wires 46 and 47 to the other rail by wire 43^P.

Each block of track is provided with one 55 or more track magnets NB, NC, etc., which form the primary of a split transformer, the secondary being carried by rolling stock, as for instance shown in the above mentioned application, Serial No. 517,391, and the control of the track magnets NB, NC, etc., is the sole function of the above described relays.

The relays QB, QC, QD, SB, SC, SD and 60 SDX may be omitted when conventional wayside signal circuit relays, which may

happen to be already installed, are provided with available extra contacts as is occasionally the case. In this event the extra contacts may be called upon to open and close the circuits of the magnets NB, NC, etc. in 70 a manner similar to that described below with respect to the above mentioned relays which are controlled by the presence or absence of rolling stock on a particular block and on the block ahead and by the time that 75 rolling stock remains upon the block.

The track magnets NB, NC, etc. are energized periodically through the relays from a source of alternating current 50 through wires 51 and 52 connected to wires 53 and 54 which parallel the track throughout its length, but are illustrated at blocks A, B, C, D and E only. Wires 53 and 54 are tapped at intervals by other wires 55^A, 55^B, 55^C and 55^P and 60^B, 60^C, 60^P and 60^E, which lead to 85 contacts of the relays.

Rolling stock indicated by a pair of wheels W is shown at the middle of block C traveling in the direction of the arrow.

When wheels W entered block C the rails 90 were short-circuited by them, therefore windings 10^C and 30^C of relays QC and SC which had been fed from the rails became de-energized, closing an alternating current circuit as follows: wire 53, wire 55^C, contact 95 slide 34^C, contact bar 32^C, contact slide 33^C, wire 36^C, contact 15^C, contact bar 12^C, contact 14^C, wire 57^C, track magnet NC, wire 58^C, track magnet NC², wire 59^C and contact 16^P of relay QD, the armature 11^P of which 100 is in the up-position, because no rolling stock is on block D. The circuit is continued from contact 16^P through contact bar 13^P, contact 17^P, wire 60^P and to wire 54.

Thus the magnets NC and NC² of block C 105 became energized as soon as rolling stock had entered the block, but not before, the object being to economize the alternating current by only closing the circuits through the track magnets when an impulse from 110 them is required for the control of rolling stock upon the block.

As the wheels W proceed from the entrance to the indicated position in the middle of block C, time is elapsing and the 115 armature 32^C and contact bar 32^C are slowly falling. In the indicated position contact bar 32^C has fallen half-way, and should rolling stock indicated by the wheels W be stopped on the block C, the circuit above 120 described would be broken at contact slide 34^C, contact bar 32^C, and contact slide 33^C in, for instance 90 seconds after the winding 30^C had been de-energized by the rails being short circuited by wheels W, and magnets NC and NC² would then become dead. The object of this arrangement of relay SC 125 is to prevent rolling stock stopping at the end of, for instance, block C and a following train entering block C slowly against 130

signals and then receiving a magnetic impulse from magnet NC, which would reset its automatic control device to clear as described in the above mentioned application, 5 Serial No. 517,391.

It should be noted that the circuit through track magnets NC and NC² passes through contact 16^D, contact bar 13^D and contact 17^D of relay QD, and that if rolling 10 stock had been upon block D the circuit would have been broken at relay QD, because the winding 10^D would have become de-energized due to the short circuiting of the rails of block D, and thus the track 15 magnets of block C could not have been energized until the rolling stock had moved off block D and winding 10^D became energized from the rails of block D.

It should also be noted that when the 20 wheels W are in the indicated position short circuiting the rails of block C the circuit through track magnets NB and NB² is broken at contact 16^C, contact bar 13^C, and contact 17^C of relay QC, so that the track 25 magnets of block B cannot be energized and made alive while rolling stock is on block C.

Block D is a block of extra length and for that reason it is not desirable that the presence 30 of rolling stock on block E should affect rolling stock entering block D, but should only affect such rolling stock when it reaches the position of braking distance with respect to block E, therefore track 35 magnets ND and ND² are positioned with relation to the end of block D and not with relation to its entrance. Blocks B and C are blocks of normal length which may be assumed to be about 4000 feet, which is 40 usually considered braking distance.

When rolling stock enters block D, armature 11^D becomes de-energized and drops from the indicated position and the rolling stock receives a magnetic impulse from the 45 extra track magnet NDX through relay SDX via the following alternating current circuit: wire 55^C, wire 70, contact slide 33^{DX}, contact bar 32^{DX}, contact slide 34^{DX}, wire 71, track magnet NDX, wire 72, contact 19, 50 contact bar 18, contact 20, wire 73, wire 60^D and wire 54.

It will be observed that in general rolling stock on a block prevents the track magnets on the block behind being made alive, and 55 that should a train become stalled on any block the magnets after being energized become dead in a predetermined interval of time, so as to prevent a train creeping up from the block behind, receiving a track 60 magnet impulse as it enters an occupied block and so being permitted to advance at full speed, in accordance with the operation of the device of the before mentioned application, Serial No. 517,391.

65 There are other dangers in the operation

of railroads than collision of rolling stock, such as crossing busy highways when the gates are up, going around a sharp curve at excessive speed, running into an open switch at full speed, crossing a frail bridge, or a 70 railroad crossing at high speed, running into an open drawbridge, etc., all of which, and perhaps others, I aim to prevent by breaking the track magnet circuit when a 75 full stop of the rolling stock should be made, or by omitting a track magnet where a train should be slowed down.

At the end of block E, Fig. 2, a busy highway 100 is shown crossing the railroad track and the track magnet circuit is completed in 80 series with a switch 101 in wire 58^E, carried by a gate 102 at the crossing, so that when the gate 102 is opened rolling stock receives no magnetic track impulse in block E and is automatically brought to a stop at 85 the highway 100.

At the end of block F a sharp curve occurs at which a train should slow down, and the second magnet is omitted, as shown 90 in the drawing.

Block G is provided with a switch 110, and to avoid the entrance of rolling stock into this switch without the train being first brought to a stop, one of the switch tongues 95 111 is provided with an insulating button 112 which thrusts the electrical contact blade 113 out of contact with the contact 114 and thus breaks the circuit through the track magnets NG and NG² at wire 59^G.

Block H crosses a bridge near its end and 100 therefore the first track magnet of this block is omitted, so that rolling stock approaches the bridge entrance at caution speed.

The cross-over at the entrance to block J makes it necessary for the second magnet of 105 block I to be omitted, so that speed will be reduced for the cross-over.

Block K consists of a drawbridge rotatable 90 degrees in the direction of the curved arrow 120 and to prevent a train running into it when it is open, I mount a retaining bar 121, provided with an insulating button 122, upon one of the tracks of the draw. Insulating button 122 holds closed a self-opening electrical switch 123, which 110 opens in the direction of the curved arrow 124 when the draw opens in the direction of the arrow 120. Switch 123 is in circuit with wire 58^J of block J, so that the track magnets of block J become de-energized when 115 the draw of block K is open and rolling stock is automatically stopped at the end of block J.

For the purposes of this application the 120 positions of the two magnets on a normal block of track 4000 feet in length may be assumed to be as follows: first magnet 200 feet from entrance of the block, second magnet 2200 feet from entrance of the block 125 and 1800 feet from the end of the block. 130

This gives a normal intermagnet distance of 2000 feet. With this spacing of the magnets a minimum of 5800 feet of unobstructed track will always be found ahead of a live magnet.

I do not limit myself to the construction shown and the scope of my invention is measured by my claims.

I claim:

- 10 1. A long block of track, a circuit normally unbridged by rolling stock between the rails and designed to be short circuited by rolling stock when the block is occupied, a relay connected across the rails designed to be de-energized by the short circuiting of the rails and to then close a track magnet circuit through a track magnet at the entrance of the long block irrespective of whether
- 15

the block ahead is clear or occupied and to close a second track magnet circuit including a second track magnet through a relay of the block ahead when the block ahead is unoccupied but not when the block ahead is occupied.

2. A block of track, a track circuit normally closed between the rails and designed to be short circuited by rolling stock, a relay in the track circuit designed to be de-energized by the short circuiting of the rails, close a track magnet circuit in the block, open a track magnet circuit in the block behind and a delayed action relay in the track circuit designed to open the track magnet circuit after a predetermined time interval.

MEYER D. MINNICK.
